UNITED STATES PATENT OFFICE.

HARRY A. DOUGLAS, OF BRONSON, MICHIGAN.

INTERNAL-COMBUSTION ENGINE.

Application filed July 23, 1924. Serial No. 727,727.

To all whom it may concern:

Be it known that I, HARRY A. DOUGLAS, a citizen of the United States, residing at Bronson, in the county of Branch and the State of Michigan, have invented a certain new and useful Improvement in Internal-Combustion Engines, of which the following is a full, clear, concise, and exact description.

10 My invention relates to an internal combustion engine employing a chamber in which the gaseous fuel is initially compressed and is thereafter passed therefrom to the cylinder which contains the working piston, the explosion occurring after the transfer of the compressed fuel to the working cylinder has been effected.

In the preferred embodiment of the invention, the crank shaft and piston of the 20 engine cooperate to effect relative reciprocation of two cylinders which cooperate in governing the engine, one of these cylinders constituting the working cylinder that receives the piston.

25 The invention will be more fully explained in connection with the accompanying drawing in which Fig. 1 is a transverse sectional view showing the engine at the initiation of the explosion; Figs. 2, 3, 4 and 5 are sectional views illustrating different stages of operation; and Fig. 6 is a sectional view on line 6—6 of Fig. 1.

The invention illustrated includes an external cylinder 1 and an interior working cylinder 2. These cylinders are telescopically related and are respectively provided with adjacent end walls 3 and 4 which, with the vertical walls thereof, define a fuel receiving chamber of variable capacity. A 35 piston 5 is reciprocable within the inner cylinder 2, this piston being connected in any suitable way with the engine shaft 6, as by means of the pitman 7 connected at one end with the wrist pin 8 that is 40 within the piston and at its other end with the crank pin 9, carried upon the outer end of the crank 10 that is provided upon the shaft 6.

Mechanism is employed for effecting relative reciprocation of the cylinders. In the 50 preferred embodiment of the invention, the inner cylinder 2 is alone reciprocated, the outer cylinder 1 being desirably upon the engine crank case 11 from which crank case 55 lubricant is supplied to the wearing surfaces of the cylinders, the piston and the pitman

connections. The mechanism illustrated for reciprocating the inner cylinder 2 is inclusive of a block 12 splined upon the pitman and pressed outwardly by a spring 13 surrounding the pitman and bottomed thereon. The cylinder 2 is partially closed by a plug 14 screwed in its inner end, a narrow slot 15 (Fig. 6) being left, within which the pitman may play. The cylinder 2 takes the 60 thrust of the spring 13 through the intermediation of the block 12 and plug 14. The spring 13 moves the cylinder 2 outwardly upon the first part of the outward stroke of this cylinder, the outwardly moving piston 70 engaging the shoulder 16 in the outer end of the cylinder 2 to complete the outward movement of the cylinder 2.

The engine illustrated, being a two stroke per cycle engine, explodes previously compressed gaseous fuel and prepares for the reception of a fresh charge of fuel during the downward or inward stroke of the engine piston. During this downward stroke, 75 vacuum is partially effected in the space between the cylinder end walls 3 and 4 due to the engagement of the piston with the top side of plug 14 that is effected when the piston reaches the mid-portion of its inward or downward movement, the spring 13 then 80 yielding to preserve the normal relation of the pitman and engine crank. During the first part of this downward movement, vacuum is effected between the end walls 3 and 4 of the cylinders. When the inward 85 or downward movement of the piston and of its cylinder 2 are nearing completion, the fuel intake port 17 is opened and the fuel rushes into the space between said cylinder end walls to replace the vacuum, Fig. 3. 90 When the intake port is opened, the port 18 in the inner cylinder, through which compressed fuel was received, as will appear, is placed in register with the exhaust port 19 that is provided in the outer cylinder 1 so 95 that the piston, in its outward or return movement, may force the expulsion of the spent gas from the cylinder 2, an operation known as scavenging. During the scavenging motion of the piston, the spring 13 is 100 effective to close ports 17 and 18 and to initiate the compression of the fresh fuel in the space between the cylinder end walls 3 and 4. The compression of the fuel is 105 thereafter mainly effected by the outwardly moving piston due to its engagement with the shoulder 16 of the inner cylinder, Fig.

5. The bore of the cylinder 2 has a lateral recess extension 20 with which the port 18 is brought into communication. When the compression of the fuel has been completed, 5 the recess at 20 conveys the compressed fuel to the port 18 through which the fuel flows into the interior of the cylinder 2 between the end wall 4 of this cylinder and the piston, the shoulder 16 maintaining a space in 10 the cylinder 2 for receiving the compressed fuel.

The compressed fuel thus admitted to the working cylinder 2 is ignited by any suitable ignition means such as a spark plug 21 whose circuit is governed by some engine driven device to cause the sparking and consequent ignition to occur upon the transfer of the compressed fuel. As illustrated, plug 21 is carried by the outer cylinder 1 in the 15 recess 20, although the invention is not to be limited to the assembly of the igniting means directly with the outer cylinder. The fuel is exploded while the cylinder end walls are in engagement, the piston being 20 moved inwardly along the inner cylinder until it engages the block 14 carried by the inner cylinder, with results effected in orderly sequence, as hereto set forth.

Changes may be made without departing 30 from my invention.

Having thus described my invention, I claim:—

1. An internal combustion engine including two telescopically related cylinders having adjacent portions defining a chamber of variable capacity, there being ports for admission of fuel and the exhaustion thereof when spent and for admitting fuel from the chamber of variable capacity into the 35 inner cylinder, and valving means governed by the engine and governing said ports; a piston in the inner cylinder; yielding motion transmitting mechanism interposed between the engine crank and the inner cylinder to move this cylinder in a fuel compressing direction; and ignition means in position to ignite the fuel passed into the inner cylinder from the chamber of variable capacity.

50 1. An internal combustion engine including two telescopically related cylinders having adjacent portions defining a chamber of variable capacity, there being ports for admission of fuel and the exhaustion thereof 55 when spent and for admitting fuel from the chamber of variable capacity into the inner cylinder and valving means governed by the engine and governing said ports; a piston in the inner cylinder; motion transmitting mechanism interposed between the engine crank and the inner cylinder to move this cylinder in a fuel compressing direction partially throughout the compression stroke of this cylinder, the piston having 60 lost motion engagement with the inner cyl-

inder when moving in the compressing direction of the latter to complete this compression; and ignition means in position to ignite the fuel passed into the inner cylinder from the chamber of variable capacity.

70 3. An internal combustion engine including two telescopically related cylinders having adjacent portions defining a chamber of variable capacity, there being ports for admission of fuel and the exhaustion thereof 75 when spent and for admitting fuel from the chamber of variable capacity into the inner cylinder, and valving means governed by the engine and governing said ports; a piston in the inner cylinder; yielding motion transmitting mechanism interposed between the engine crank and the inner cylinder to move this cylinder in a fuel compressing direction partially throughout the compression stroke of this cylinder, the piston having 80 lost motion engagement with the inner cylinder when moving in the compressing direction of the latter to complete the compression; and ignition means in position to ignite the fuel passed into the inner cylinder from the chamber of variable capacity.

85 4. An internal combustion engine including two telescopically related cylinders having adjacent portions defining a chamber of variable capacity, there being ports for admission of fuel and the exhaustion thereof 90 when spent and for admitting fuel from the chamber of variable capacity into the inner cylinder, and valving means governed by the engine and governing said ports; a piston in the inner cylinder, the piston having lost motion engagement with the inner cylinder when moving in the compressing direction of the latter to complete the compression; and ignition means in position to ignite the fuel passed into the inner cylinder from the chamber of variable capacity.

95 100 5. An internal combustion engine including two telescopically related cylinders having adjacent portions defining a chamber of variable capacity, there being ports for admission of fuel and the exhaustion thereof 105 when spent and for admitting fuel from the chamber of variable capacity into the inner cylinder, and valving means governed by the engine and governing said ports; a piston in the inner cylinder, the piston having lost motion engagement with the inner cylinder to move it in a compressing direction; and ignition means in position to ignite the fuel passed into the inner cylinder from the chamber of variable capacity.

110 115 6. An internal combustion engine including two telescopically related cylinders having adjacent portions defining a chamber of variable capacity, there being ports for admission of fuel and the exhaustion thereof 120 when spent and for admitting fuel from the chamber of variable capacity into the inner cylinder.

- cylinder, and valving means governed by the engine and governing said ports; a piston in the inner cylinder, the piston having lost motion engagement with the inner cylinder to move it to enlarge said chamber; and ignition means in position to ignite the fuel passed into the inner cylinder from the chamber of variable capacity.
7. An internal combustion engine including two telescopically related cylinders having adjacent portions defining a chamber of variable capacity, there being ports for admission of fuel and the exhaustion thereof when spent and for admitting fuel from the chamber of variable capacity into the inner cylinder, and valving means governed by the engine and governing said ports; a piston in the inner cylinder; motion transmitting mechanism interposed between the engine crank and the inner cylinder to move this cylinder in a full compressing direction partially throughout the compression stroke of this cylinder, the piston having lost motion, engagement with the inner cylinder when moving in the compressing direction of the latter to complete the compression and when moving in the reverse direction to enlarge said chamber and open the inlet port; and ignition means in position to ignite the fuel passed into the inner cylinder from the chamber of variable capacity.
8. An internal combustion engine including two telescopically related cylinders having adjacent portions defining a chamber of variable capacity, there being ports for admission of fuel and the exhaustion thereof when spent and for admitting fuel from the chamber of variable capacity into the inner cylinder, and valving means governed by the engine and governing said ports; a piston in the inner cylinder; yielding motion transmitting mechanism interposed between the engine crank and the inner cylinder to move this cylinder in a fuel compressing direction partially throughout the compression stroke of this cylinder, the piston having lost motion engagement with the inner cylinder when moving in the compressing direction of the latter to complete the compression and when moving in the reverse direction to enlarge said chamber and open the inlet port; and ignition means in position to ignite the fuel passed into the inner cylinder from the chamber of variable capacity.
9. An internal combustion engine including two telescopically related cylinders hav-
- ing adjacent portions defining a chamber of variable capacity, there being ports for admission of fuel and the exhaustion thereof when spent and for admitting fuel from the chamber of variable capacity into the inner cylinder, and valving means governed by the engine and governing said ports; a piston in the inner cylinder; motion transmitting mechanism interposed between the engine crank and the inner cylinder to move this cylinder in a full compressing direction partially throughout the compression stroke of this cylinder, the piston having lost motion, engagement with the inner cylinder when moving in the compressing direction of the latter to complete the compression and when moving in the reverse direction to enlarge said chamber and open the inlet port; and ignition means in position to ignite the fuel passed into the inner cylinder from the chamber of variable capacity.

In witness whereof, I hereunto subscribe my name.

HARRY A. DOUGLAS.
